his Attorney

UNITED STATES PATENT OFFICE.

CECIL A. HEAD, OF ROYAL OAK, MICHIGAN.

ELECTRIC RADIATOR.

Application filed February 25, 1922. Serial No. 538,204.

To all whom it may concern:

Be it known that I, CECIL A. HEAD, a subject of the King of England, and a resident of Royal Oak, in the county of Oakland and State of Michigan, have invented a new and useful Improvement in Electric Radiators, of which the following is a specification.

My invention relates to electric radiators and its principal object is to provide a radiator of this type wherein the water supply is retained in a state of evaporation for substantially the entire length of time of operation of the radiator.

15 It is another object of the invention to provide an electric radiator which will radiate a maximum amount of heat in a minimum period of time with a minimum supply of electricity.

20 A further object of the invention is to provide a portable electric radiator wherein the supply of electric current will be automatically cut off upon total evaporation of the water supply, thus the unnecessary expenditure of electric energy is obviated.

With the preceding and other objects and advantages in mind, the invention consists in the novel combination of elements, constructions and arrangement of parts and 30 operations to be hereinafter fully referred to, claimed and illustrated in the accompanying drawing, wherein:

Figure 1 is a vertical sectional view of an electric radiator constructed in accordance 35 with my invention.

Fig. 2 is an end elevation of the same,

Fig. 3 is a top plan view of the electrical heating unit embodied in the invention, and

Fig. 4 is a vertical sectional view of the 40 same.

Referring to the drawing in detail wherein similar characters of reference denote similar parts throughout the several views, the numeral 5 designates a vertically disposed cylinder or generating chamber in the lower end of which a cup or water reservoir 6 is threaded. Threaded upon the upper end of the cylinder or generating chamber 5 is a closure 7.

45 Extending horizontally from the cylinder or generating chamber 5 at diametrically opposite points are vertically aligned radiating tubes 8 having communication with the interior of this cylinder or generating chamber 5. Communicating with the outer ends 55 of the radiating tubes 8 are vertically dis-

posed return pipes 9 whose lower ends receive the upper ends of supporting legs 10. In this embodiment of the invention only two sets of radiating tubes 8 are illustrated. It is within the scope of my invention, however, to employ as many sets of these tubes as may be found practical.

My invention provides an improved heating unit to vaporize the water contained in 65 the water reservoir 6. This heating unit embodies a rectangular chamber 11 constructed of porcelain or other non-conducting material having a flange 12 at its upper edge which is secured to the bottom of the cup or reservoir 6 by fastenings 13. Packing 14 is interposed between the flange 12 and bottom of the cup or reservoir 6 to afford a water tight joint between these parts. Arranged in the chamber 11 and spaced from 70 the sides thereof are positive and negative electrodes 15 and 16 respectively, the latter being electrically connected with electricity conductors 17 in circuit with any suitable source of electrical energy, not shown. As 75 shown in Fig. 3, each of the electrodes 15 and 16 comprises a longitudinal bar 18 from which a plurality of spaced right-angularly disposed fins or plates 19 extend. These plates or fins of these electrodes have interfitting engagement and are spaced from each other. Carried by the cup or water reservoir 6 is a laterally extending water gage 20 80 whereby to indicate the liquid level of the contents of the cup or water reservoir.

85 In the operation of my improved heater the water from the cup or reservoir 6 enters the spaces between the fins or plates 19 and thereby completes the circuit through the electrodes. The electric current passing through the water and finding resistance therein, quickly boils and evaporates the same and steam rises in the cylinder or generating chamber 5, thence circulating 90 through the radiating tubes 8. As the water is condensed it passes through the lowermost tubes 8 and flows into the cup or generating chamber 6 to be again vaporized. Should the entire body of water become totally 95 vaporized the circuit between the electrodes would be broken. It will be thus seen that the supply of electrical energy will only be consumed while the radiator contains water. 100 It is to be understood that the form of my invention herein shown and described is 105 to be taken as a preferred example of the same, and that various changes in the shape,

size and arrangement of parts may be resorted to without departing from the spirit of the invention or the scope of the subjoined claims.

5 Having thus described my invention, what I claim as new and desire to secure and protect by Letters Patent of the United States is:

1. An electrical heater including a receptacle having an insulated bottom, a pair of electrodes supported on the bottom and each including a bar and spaced right-angularly disposed plates having interfitting engagement and spaced from each other, the 15 circuit between the electrodes being com-

pleted by the body of water contained in the receptacle, and broken upon the exhaustion of the water supply.

2. The combination with a tubular generating chamber of a bottomless water reservoir secured to the lower end thereof, a bottom secured to the water reservoir of non-conducting material, and electrodes arranged in the bottom comprising longitudinal bars and right angularly extending interfitting 20 plates arranged in spaced relation and adapted to have electrical connection with each other by the water contained in the reservoir. 25

CECIL A. HEAD
